UNITED STATES PATENT OFFICE.

GEORGE SMITH, OF JERSEY CITY, NEW JERSEY.

CLIP FOR DETECTOR-BARS.

SPECIFICATION forming part of Letters Patent No. 721,975, dated March 3, 1903.

Application filed December 11, 1902. Serial No. 134,801. (No model.)

To all whom it may concern:

Be it known that I, GEORGE SMITH, a citizen of the United States, and a resident of Jersey City, in the county of Hudson and State of New Jersey, have invented a new and Improved Clip for Detector-Bars, of which the following is a full, clear, and exact description.

This invention relates to a means for supporting detector-bars; and the object sought is to provide a clip lying closely and compactly alongside the rail and adjustable to rails of various sizes and to meet other conditions liable to arise in railway construction.

This specification is an exact description of one example of the invention, while the claims define the actual scope thereof.

Reference is to be had to the accompanying drawings, forming a part of this specification, in which similar characters of reference indicate corresponding parts in all the views.

Figure 1 is an inner side elevation of the clip. Fig. 2 is a cross-section on the line 2 2 of Fig. 6. Fig. 3 is an outer side elevation of the motion-plate. Fig. 4 is an inner side elevation of the same. Fig. 5 is a section on the line 5 5 of Fig. 4. Fig. 6 is an outer side elevation of the clip and motion-plate, showing the detector-bar lowered; and Fig. 7 is a similar view showing the detector-bar raised.

The body of the clip is formed with a horizontal groove a for the reception of the outer base-flange of the rail and with a transverse orifice a' receiving the outer end of the hook-bolt b , the nut whereof bears against the outer face of the body, the hook-bolt being passed under the rail and engaged with the inner flange thereof. In its upper portion the body of the clip is formed with a vertically-elongated orifice a^2 running transversely through it and communicating at its inner side with a groove a^3 , formed in the inner face of the clip-body and running upward from slightly below the orifice a^2 to the upper extremity of the body. In this groove a^3 is set loosely the carrier c . Said carrier is held rigidly in place and yet capable of vertical adjustment by means of a bolt d , which has at its inner end an enlargement d' , with an annular flange d^2 , said parts d' and d^2 forming a flanged stud and the enlargement d' bearing against the carrier c to hold it. d^3 represents the nut on

the bolt d , and d^4 represents an antifriction-collar set on the enlargement d' and lined with a suitable gasket, as illustrated. At its upper portion the carrier c is provided with an inwardly-projecting lug c' , which lies just above the aforesaid flanged stud d' d^2 .

e indicates the motion-plate, which is formed on its inner side at each end with an inwardly-projecting lug e' . These lugs are adapted to bear under the detector-bar f and assist in holding the detector-bar and motion-plate connected. Complete connection is effected by bolts passed through the parts e and f , for which purpose the motion-plate is provided with orifices e^2 , as shown. On its outer side the motion-plate is formed with a cam e^3 , the middle of which is dipped downward, as best shown in Fig. 3. The flange d^2 lies against the front face of the motion-plate, and the said cam e^3 bears its lower face on the collar d^4 , as indicated in Fig. 2. Now it is clear that by this arrangement any longitudinal motion of the detector-bar must be accompanied by a vertical movement and that this vertical movement is brought about by the cam e^3 riding on the flanged stud of the carrier. The lug c' prevents the detector-bar from jumping out of place owing to the engagement between the said lug and the top face of the cam e^3 . The detector-bar is connected with the switch mechanism in the usual manner.

It is clear that by this construction the clip may be placed snugly alongside of the rail and its working parts be held above the base-flange. In certain constructions heretofore employed moving parts of the clip were placed below the base-flange or adjacent thereto, and they are thus liable to become clogged with ice and ballast from the road-bed, so as to prevent the proper working of the detector-bar. This will be entirely obviated by the construction forming the subject-matter of my invention. Further, it will be observed that the carrier c may be very readily adjusted so as to place the detector-bar at any desired position with respect to the ball of the rail. The bolt b may be withdrawn at will, so that the clip may instantly be fastened to a rail of any sort. This avoids providing separate clips for different sizes of rails.

Various changes in the form, proportions,

and minor details of my invention may be resorted to at will without departing from the spirit and scope thereof. Hence I consider myself entitled to all such variations as may 5 lie within the intent of my claims.

Having thus described my invention, I claim as new and desire to secure by Letters Patent—

1. The combination of a body, means for 10 fastening the same in place, said body having a portion projected upward from the plane of the base-flange of the rail, a carrier adjustably mounted on the upper portion of the body and having a lug projecting inward, 15 a stud projecting from the carrier below the lug, and a motion-plate having a cam bearing between the stud and lug.

2. The combination of a body, means for 20 holding it in place, a carrier-plate mounted on the body, a motion-plate having a cam thereon, and means projecting from the carrier and engaging the cam of the motion-plate, said means comprising a flanged stud and a lug above the same.

25 3. The combination of a body, means for holding it in place, said body having an upwardly-projected portion with a vertically-disposed orifice, a carrier-plate, a bolt having an enlargement engaged with the carrier-plate, said bolt being fastened in the orifice of the body, a lug projected inward from the carrier above the enlarged portion of the bolt, a motion-plate, and a cam thereon, said cam bearing between the bolt and lug.

35 4. The combination of a body, means for

holding it in place, a carrier, a bolt adjustably mounting the carrier on the body, a lug projected from the carrier, a motion-plate, and a cam carried thereon, said cam bearing between the bolt and lug. 40

5. The combination of a body, means for holding it in place, a carrier adjustably mounted thereon, two members projected from the carrier, a motion-plate, and a cam mounted on the motion-plate and bearing between the 45 said two members of the carrier.

6. The combination of a body, means for holding it in place, a carrier adjustably mounted on the body, a motion-plate having a cam thereon, and means projecting from the carrier and engaged with said cam, for the purpose specified. 50

7. The combination with a rail, of a body portion, means for fastening the same to the base-flange thereof, the body portion projecting upward from said means, a stud carried by the body portion above said means and projected inward toward the rail, a lug carried by the body above the stud and also projecting inward toward the rail, and a motion- 60 plate having a cam thereon, the cam bearing between the said stud and the lug.

In testimony whereof I have signed my name to this specification in the presence of two subscribing witnesses.

GEORGE SMITH.
